UNITED STATES PATENT OFFICE.

NOBLE H. CONGER, OF MINNEAPOLIS, MINNESOTA.

RAILWAY-TIE.

No. 921,510.

Specification of Letters Patent.

Patented May 11, 1909.

Application filed October 28, 1907. Serial No. 399,510.

To all whom it may concern:

Be it known that I, NOBLE H. CONGER, a citizen of the United States, residing at Minneapolis, in the county of Hennepin and State of Minnesota, have invented certain new and useful Improvements in Railway-Ties; and I do hereby declare the following to be a full, clear, and exact description of the invention, such as will enable others skilled in the art to which it appertains to make and use the same.

My invention has for its object to provide an improved railway tie, and to this end it consists of the novel devices and combinations of devices hereinafter described and defined in the claims.

In the accompanying drawings which illustrate the invention, like characters indicate like parts throughout the several views. Referring to the drawings, Figure 1 is a view chiefly in side elevation, but with some parts broken away and some parts in vertical section, showing my improved railway tie, some parts being removed. Fig. 2 is a plan view of the parts shown in Fig. 1, some parts being removed and some parts being broken away. Fig. 3 is an enlarged vertical section taken through the reinforced concrete body of the tie, on the line $x^3 x^3$ of Fig. 1; and Fig. 4 is a detail of a nut locking plate used on the interior of the tie body.

The body 1 of the tie is of metal reinforced concrete and it is arched, that is, is formed with a longitudinal passage or channel 2 that extends from end to end thereof. Said hollow tie will serve as a culvert or water conduit. The preferred arrangement of the metal reinforcements of the tie body is as shown in the drawings and is as follows: Upper rods 3, lower rods 4 and intermediate rods 5 are extended from end to end of the tie body and these rods, at suitable intervals, are tied and bound together by transversely extended heavy wires 6. Each wire 6 is wrapped around the said several rods and the outer portion thereof forms approximately a rectangle, while the inner portion thereof forms triangles with the upright side portions and connects the intermediate rods 5 just above the arched passage 2. These truss wires or rods 6 very greatly strengthen the concrete body 1 against crushing strains and against spreading at the base and, as is evident by inspection particularly of Fig. 3, they produce a reinforcement entirely around

the arched passage 2. The arched passage, of course, very greatly reduces the weight of the tie body and minimizes the amount of concrete necessary in its construction. The longitudinally extended rods 3, 4 and 5 very greatly increase the tensile strength of the tie body and enable the same to withstand the vertical strains put upon the same by the load of trains passing over the rails that are secured to the tie. Laterally spaced truss rods 7 are also extended from end to end of the tie body 1 and these are preferably passed through the triangular side spaces formed by the transverse truss rods or wires 6. The ends of the truss rods 7 terminate near the base of the tie body 1, while the intermediate portions thereof extend well upward toward the top of the tie body and are preferably looped at 7^a, (see Figs. 1 and 3). These loops 7^a very greatly increase the strength of the intermediate portion of the tie body. Also embedded in the concrete tie body 1 above the arched passage 2 is a flanged and channel-shaped anchor plate 8 that is perforated to permit the concrete to join from the opposite sides thereof. This anchor plate 8 is surrounded by the upper portion of the transverse truss rods or wires 6, as clearly shown in Fig. 3.

In Figs. 1 and 2 the numeral 9 indicates the main track rails, and in Fig. 1 the numeral 10 indicates a guard rail. These rails do not rest directly upon the concrete body of the tie, but rest directly on the metal bearing plates 11 that are pivotally connected to the body of the tie by pivot bolts 12. These pivot bolts 12 are located directly under the rails 9 and they are passed through the upper portion of the concrete tie body 1 with their threaded ends depending into the passage 2 thereof. The heads at the upper ends of the bolts 12 are preferably made flaring and are counter-sunk into slightly raised portions of the bearing plates 11, between which raised portions and the upper surface of the tie body cushioning strips or plates 13 are interposed. These cushioning strips or plates 13 may be of leather, wood, paper composition or any other slightly resilient material which will act as a cushion between the rail and the tie body. Nuts 14 are applied to the threaded lower ends of the bolts 12, and these are locked against rotation by channel-shaped lock plates 15 (see particularly Figs. 3 and 110).

4) that are provided with open slots 16, adapting them to be slid straddle of the bolts, with their depending flanges engaged with the said nuts, thereby locking the latter against rotation. The bolts 12 do not need to be drawn tight, but the nuts thereof should, nevertheless, be held against accidental displacement. As is evident, the lock plates 15 can not rotate with the arched 10 passage 2.

To secure the rails 9 to the underlying bearing plates 11, each of the latter is provided with a pair of raised and reversely projecting lock lugs or lips 17. These lock lugs or lips 17 are located one on each side of the coöperating rail; and in a direction longitudinally of the rail they are located one on each side of the pivot bolt 12. With this construction, when the bearing plate 20 is turned as indicated by dotted lines in Fig. 2, the rail may be applied in position or removed from position; and when the rail is in position and the lock plate is turned from the position indicated by dotted lines into the position indicated by full lines in Fig. 2, the lock lugs or lips 17 will engage and overlap the base flange of the rail and thus securely hold the rail in proper position on the tie.

30 To secure the bearing plates 11 in their operative positions, the heads of nutted bolts are embedded in the tie body 1 and their threaded ends work in slots 18 of said plates 11, and nuts 19 on the upper ends of said bolts serve to rigidly clamp the inner ends of the said bearing plates 11 to the tie body. The slots 18 permit slight adjustments of the plates 11 necessary to tighten the lock lugs 17 onto the rail flange. The 40 rails 9 are further held against outward canting movements by folded metal thrust plates or braces 21, the folded inner portions of which engage under the outer flange of the tread of the rail. These thrust plates 21 are clamped and held in working position by clamping blocks 22 which, in turn, are clamped in working position by nutted bolts 23. The headed ends of these bolts 23 are embedded in the concrete body of the tie and are anchored therein by the flanges of the channel-shaped anchor plate 8 through which the said bolts are passed and with which the heads of said bolts are engaged.

The so-called thrust plates 21 are preferably constructed of sheet steel and they are slightly resilient so that they are better able to stand the pounding shocks imparted to the rails by the lateral thrust of a car or engine.

60 Where it is desirable, the guard rail 10 above noted may be directly secured to the inner portion of either one of the bearing plates 11. To accomplish this, short nutted bolts 24 have their heads counter-sunk into the bearing plates 11 and serve to secure

angular metal clamps 25 to said bearing plate and to the base flange of the said guard rail.

As shown at the left in Fig. 2, the lower fold of the thrust plate 21 is provided at its ends with under-turned lock lips 21* that embrace the ends and underlie the outer end of the bearing plate 11 and thus lock the said thrust plate against endwise displacement.

What I claim is:

1. A hollow concrete railway tie having embedded therein longitudinally extended reinforcing rods 3, 4 and 5, and a multiplicity of transversely extended reinforcing wires or 80 rods 6 surrounding the opening in said tie body, wrapped about the said rods 3, 4 and 5 and forming triangular portions at opposite sides of the tie, substantially as described.

2. A concrete railway tie having embedded therein longitudinally extended reinforcing rods, a longitudinally extended perforated anchoring plate, and a multiplicity of transversely extended reinforcing rods or wires embracing said longitudinally extended rods and surrounding said anchoring plate, substantially as described.

3. The combination with a hollow concrete railway tie having a longitudinally extended passage, of longitudinally extended reinforcing rods embedded in said tie body, a perforated longitudinally extended anchoring plate embedded in said tie body, and a multiplicity of transversely extended reinforcing wires or rods constituting transverse truss reinforcements and surrounding said anchoring plate and the passage in said body, substantially as described.

4. The combination with a hollow tie body, of bearing plates having oppositely disposed and laterally spaced lock lugs for engagement with the opposite edges of the foot flanges of the rails, bolts pivotally connecting said bearing plates to said tie body, nuts applied to the lower ends of said bolts within the channel or passage of said tie body, nut-locking plates applied to said nuts within said channel, and means for securing said bearing plates in operative position against rotation, substantially as described.

5. The combination with a tie body, of metal bearing plates pivotally connected thereto and provided with oppositely extended and laterally spaced lock lugs or lips for engagement with the opposite edges of the foot flanges of the main rails, means for securing said bearing plates in operative positions against rotation in respect to said tie body, and independent means for securing a guard rail to one or more of said bearing plates, substantially as described.

6. The combination with a tie body, of bearing plates pivotally connected thereto

and provided with oppositely disposed and laterally spaced lock lugs or lips for engagement with the opposite edges of the foot flanges of the rails, folded metal thrust plates applied to the outer sides of the rails, and clamping blocks belted to said tie body and holding said thrust plates in working position, substantially as described.

7. The combination with a tie body, of a bearing plate pivotally connected thereto and provided with oppositely disposed and laterally spaced lock lugs for engagement with the opposite edges of the foot flange of the rail, a thrust plate resting on the outer

end of said bearing plate and engaging the outer side of the rail, said thrust plate having under-turned lips that engage the edges of the outer end of said bearing plate to hold said thrust plate against endwise displacement, and a device clamping said thrust plate to said bearing plate, substantially as described.

In testimony whereof I affix my signature in presence of two witnesses.

NOBLE H. CONGER.
